CLAIM

The ornamental design for a display screen with an animated graphical user interface as shown and described.

DESCRIPTION

FIG. 1 is a front view of a first image in a sequence for a display screen with an animated graphical user interface showing our new design;

FIG. 2 is a front view of a second image thereof; and,
FIG. 3 is a front view of a third image thereof.

The cross-hatched area of the animated graphical user interface having forwardly slanted thinly spaced lines illustrates a contrasting appearance with the cross-hatched area of the graphical user interface having rearwardly slanted widely spaced lines. The appearance of the animated graphical user interface sequentially transitions between the images shown in FIGS. 1, 2, and 3. The process or period in which an image transitions to another forms no part of the claimed design. The peripheral dash-dot-dot lines illustrate a display screen or portion thereof and form no part of the claimed design. The dashed broken lines and the dash-dot-dot lines within the peripheral dash-dot-dot lines illustrate portions of the graphical user interface, which form no part of the claimed design.

1 Claim, 3 Drawing Sheets
